In Great Britain June 13, 1949

14 Claims. (Cl. 216—52)

1 This invention relates to a machine for applying labels to cylindrical objects such as, for example, glass bottles. More particularly but not solely the invention relates to machines of the kind comprising gum plates mounted for reciprocating movement and adapted first to receive adhesive thereon and then to receive a label from a hopper and to bring the label to a position where the label may be transferred from the gum plates to the object during movement of the object and label transversely of the reciprocating movement of the gum plates.

It is an objective of the invention to enable the labels to be applied to cylindrical objects correctly and reliably. A further object of the invention is to enable the objects to be automatically fed to labelling devices from a row of objects so that they do not have to be entered by hand one at a time into the labelling device. A still further object of the present invention is to provide means whereby the labels can be applied completely around the object or even overlapping.

To this end, the present invention consists in a machine for applying labels to cylindrical objects, wherein means are provided for gumming and applying a label to the object at one part of its length and further means are provided for thereafter rolling one object along a preferably plane surface thereby to roll the label on the object and apply it firmly thereto.

The plane surface is preferably constituted by a strip of rubber, cork, or other resilient material and the object is rolled along said surface by at least one endless conveyor belt spaced apart from and in parallel relation to said surface by an amount substantially equal to the diameter of the object whereby the object is rolled between the belt and the plane surface. The plane surface may be adjustably mounted so as to vary the distance between it and the conveyor belt to accommodate objects of different sizes.

According to a further feature of the invention means are provided whereby a row of objects on a downwardly inclined feed chute are picked off one at a time by a reciprocating label applying device, a rest which after initial application of the label to the object, being moved to bring the object into contact with the endless conveyor belt which rolls the object off the rest on to and along the plane surface.

The feed chute, the plane surface and the conveyor belt are disposed, according to a further feature of the invention, one above the other on the same side of the machine as the reciprocating

rest, whereby a compact apparatus is provided and the objects are fed approximately back to the same position as the position where the operator places the objects in the feed chute.

5 According to a still further feature of the invention the gum plates are caused to pause during the reciprocating movement thereof at a position where the reciprocating rest lies below and towards one side of the opening in the gum plates whereby the label applying device may push a label lying on said gum plates through said opening on to an object on the rest and affix the label on to the object at a point adjacent one end of the label.

15 In order that the invention may be more readily understood reference is made to the accompanying drawings which illustrate diagrammatically and by way of example, one embodiment of a machine for labelling bottles or the like objects in accordance therewith, and in which:

Figure 1 is the front elevation of the machine;

Figure 2 is a sectional side elevation taken on the line II—II of Figure 3;

Figure 3 is a plan;

Figure 4 is a detail of the label box reciprocating movement;

Figure 5 is a side elevation, partly in section, of the label applying device, the bottle rest and the gum plates;

Figure 6 is a detail of the label applying device and the reciprocating mechanism therefor;

Figure 7 is a detail of the reciprocating mechanism for the bottle rest;

Figure 8 is a side elevation similar to Figure 2 but showing a part only of Figure 2 on an enlarged scale;

Figure 9 is a plan view of the gum plate shown in Figure 8;

Figure 10 is a front elevation similar to Figure 1 but showing a part only of Figure 1 on an enlarged scale;

Figure 11 is a side elevation similar to Figure 5 but showing a part only of Figure 5 on an enlarged scale; and

Figure 12 is a side elevation similar to Figure 2 but on an enlarged scale and showing the full outline of a cam a part only of which is shown in Figure 2.

45 In the drawings, the main groups of components comprise a gum or adhesive applying means 1, a horizontally reciprocating gum plate 2, a vertically reciprocating label box 3, a label applying means 4, a reciprocating bottle rest 5, a feed chute for the objects to be labelled 6, and a

delivery means 7. The various components are mounted in a frame-work 28 and an electric motor or other power means 29 is provided for driving the various mechanisms through suitable transmissions.

The gum applying means 1 (Figure 2) comprises a gum box or trough 8, having a positively driven gum pick-up roller 9, rotatably mounted with its periphery dipping into the gum and engaging with the surface of a transfer roller 10, also positively driven. A gum or adhesive applying roller 11 is freely mounted in one end of each of a pair of gum roller rocker arms 12 which are interconnected by a sleeve 13 mounted on a rod 14 at the rear of the machine. Arms 12 rock about a pivot 15 so as to bring the roller 11 alternately into contact with the gum transfer roller 10, and the horizontally reciprocable gum plate 19, and the horizontally reciprocable gum plate 2.

Fast on the sleeve 13 is a cranked lever 16 having a stud 17 welded thereon at the elbow of the lever to which is secured one end of a spring 18, the other end of which is fastened to a hooked rod 19 secured in the front wall 20 of the machine. Spring 18 tends to keep gum roller 11 in the position shown in Figure 2 where it is in contact with the transfer roller 10. The other end 21 of the crank lever 16 is connected by a spring 22 to the free end of a cam lever 23 pivoted at 24 in the rear wall 25 of the machine. Lever 23 carries a cam roller 26 which is urged into contact with a cam 27 by the spring 22. Cam 27 is carried by a main shaft 120 journalled in the frame 28 of the machine and driven by the motor 29 through pulley 122, belt 123, pulley 124, shaft 125, worm 126, and worm wheel 127, the latter being fast on shaft 120. Depression of lever 23 from the position shown in Figure 2 by the cam 27 moves the end 21 of crank lever 16 downwardly to rock the arms 12 downwardly and disengage the gum applying roller 11 from the transfer roller 10 and bring the same into a position in the path of the gum plate 2 to apply gum thereto.

The gum plate assembly 2 (Figures 1 to 3) reciprocates on a fixed shaft 30 secured horizontally between the front and rear walls 20 and 25, and comprises a substantially rectangular plate 31 carried on an arm 110 formed on a block 111 sliding on shaft 30. End 112 of arm 110 rests on a frame member to assist in supporting the gum plates assembly during reciprocation. Rectangular plate 31 has a rectangular opening or cut-out 32 at its forward end through which a label may be passed as will later be more fully described. Opening 32 divides the plate 31 into a pair of gum plates 33 and 34. For labels of different sizes different gum plates may be provided with different sizes of opening 32. The opening may be, say, approximately 1 1/4 inches wide for objects between half and one inch diameter. The gum plates 33 and 34 are reciprocated by a lever 35 which is rocked about a fixed pivot 36 by a cam 37, secured to the main cam shaft 120, acting through a cam roller 38, freely mounted on the lever. The cam roller 38 is held in contact with the cam 37 by a spring 39 anchored at one end to the rear wall 25 and engaging at the other end on a pin 113 welded to the lever 35. The upper end of lever 35 is forked at 115 to receive and drive pin 114 on the block 111. The cam plate assembly may also carry a type block or chase 40 for printing or stamping on the labels as they are fed by the machine.

The label box assembly 3 (Figures 2 to 4) includes a plurality of vertical fingers 41 secured in a rectangular frame comprising two rods 116, 117 and two plates 42, 142 slidably mounted on the rods. The rods are secured at one side to a plate 42a which in turn is secured to a vertical rod 43 which is journalled in bearings 55, 56 for vertical sliding movement. Each finger has an inturned nose 44 upon which a stack of labels are carried. A pressure plate 45 is urged downwardly by a follower 46 to keep the labels properly stacked and bearing against the noses 44. The lower end of rod 43 is cranked at 47 and is pivotally connected to a further rod 48. This rod is pivotally connected to a cam lever 49 pivoted at 50 in the frame of the machine. A cam 51, secured on the main cam shaft 120, engaging a cam roller 52 carried by a lever 49 actuates the rod 43 to raise and lower the label box. Cam 51 has two dwells in its surface, one of which 53 brings the label box into contact with the gum plates 33, 34, and the other 54 brings the box into contact with the type in the type block 40. In other positions of the cam the label box is raised out of the path of the gum plate assembly.

The label applying means 4 (Figures 1, 2, 3 and 5) comprise a pair of vertical slide bars 57, 58 carried on a rod 59 mounted for sliding movement in a yoke 60 secured to the front wall 20. The bars 57 and 58 are connected together in spaced parallel relationship by straps 61, 62, the latter having a stud 62a at its rear end which rides in a guide slot provided in the base of the yoke 60 to prevent any twisting movement of the bars about the rod 59. The slide bars carry label applying feet 63, 64 at their lower ends. These feet are removable so that they can be replaced by feet of a different size according to the size of the opening 32 between the gum plates 33 and 34.

The reciprocating drive to the slide bars 57, 58 comprises a lever 65 pivoted at 66 in the front wall 20, one end of which is forked at 67 to engage a stud 68 formed in or provided on a collar 69 fast on rod 59. The other end of lever 65 is connected through a stud 70 passing through wall 20 to one end of an operating rod 71. Pivotally connected at 72 to the other end of rod 71 is a cam operating lever 73 anchored at 74 to the rear wall 25 by a pivot 75. Lever 73 carries a cam roller 76 which is urged against a cam 77, secured to main cam shaft 120, by a spring 78 attached to the bottom of rod 71 and anchored at 79 to the front wall 20. The slide bars 57, 58 straddle an endless conveyor belt 80, later to be referred to, and the feet 63, 64 are adapted to pass through the opening 32 in the gum plates during reciprocating movement of the bars.

The bottle rest assembly 5 (Figures 1, 2 and 7) is mounted on the front wall 20 and comprises a vertical bar 81 carried in a trunnion 82 fast on a shaft 83 mounted for sliding movement in bearing blocks 84 and 85 secured to the rear of the wall 20. The upper end of the bar 81 is sloped at 86 downwardly to the right as viewed in Figure 2 to form with a detachable slide plate 87 a bottle rest. A series of side plates 87 of different sizes may be provided for containers of different diameter. The surface 86 and also, if desired, the plate 87 may be faced with a sheet of rubber, cork or other resilient material to act as a cushion for the article held thereon.

The rest bar 81 supports a container 100 to

one side of the opening 32 in the gum plates (see Figure 1). Bar 81 is also positioned vertically beneath the label applying slide bars 57, 58 so that the container 100 can be held between the two components as will later be described.

The rear end 88 of the trunnion 82 is connected by a spring 89 to the free end of a cam operating lever 98 fixed in the rear wall 25 at 91 by a pivot 92. The lever 98 carries a cam roller 93 urged by spring 89 into contact with a cam 94 secured to the main cam shaft 120.

The feed chute 6 (Figure 1) is secured to the front wall 20 and is inclined downwardly from left to right and at an angle substantially the same as the sloping end 86 of the rest bar 81. The bottles or other objects 100 to be labelled are fed by hand on to the projecting end 95 of the chute to roll by gravity down the chute to lie against the side of the rest bar 81 as shown in Figure 1. When the rest bar is lowered a bottle rolls on to the sloping surface 86 and as the bar is raised the remaining bottles in the chute are held back by the side of the bar 81 as shown. The chute 6 is preferably an angle section, the upstanding flange serving to line up the articles in the chute. If desired, the chute may be inclined slightly transversely to ensure that the articles are properly aligned. The chute may be adjustable in a position from front to rear of the machine and also vertically.

The endless conveyor belt 80 forming part of the delivery means 7 (Figures 1, 3 and 5) is carried by two pulleys 96 having horizontal axes, one 97 a short distance on one side of the slide bars 57, 58, and the other 98 disposed a considerable distance, for example, 18 inches to the left of the slide bars, and at a higher level so that the belt is inclined upwards to the left. Below the lower run of the belt 80 and parallel to it is a plane surface 99 constituted by a strip of rubber, cork or other resilient material 101 carried by a metal backing plate 102 which in turn is carried in brackets 103, 104 mounted for vertical adjustment on the front wall 20. The brackets are clamped in the adjusted position by nuts 105. The tension of the belt 80 is adjustable by an adjuster 130.

A wiper blade 106 which may be of resilient material, is secured to and projects beyond the right hand end of plate 102 to lie in the path of the left hand side of the rest arm 81. A collecting trough 107 constituted for example by an angle bar is secured to the upper or delivery end of the plane surface 99.

The operation of the machine is as follows:

The operator feeds the bottles or containers 100 on to the projecting end 95 of the feed chute 6. The lowermost container in the chute rolls on to the sloping surface 86 of the rest bar 81 when the latter is in its lowermost position and the rest then rises to a position just below the plane of the gum plates 33 and 34. Due to the shaping of the cam 94, the rest 81 then pauses in this position. During this movement the gum applying roller moves down and the gum plates 33 and 34 move forward to receive adhesive from the said roller. The gum plates pause below the label hopper which descends to release the lowermost label. The label hopper is then raised and the gum plates continue their movement to their extreme forward position. The label applying feet 63 and 64 then descend together until the label passes completely through the opening 32 on to the container 100 lying in the rest 81. As the container is supported at the left hand

end of the opening 32 so as to overlap the right hand edge of the left hand gum plate 34, the short left hand end of the label is applied to the container first.

- 5 The rest 81 and feet 63, 64, are then raised together with the container with the label affixed only towards its left hand end, until the container contacts the lower run of the endless belt 80 which is moving from right to left. During this upward movement the wiper 106 contacts the left hand side of the container and affixes the left hand end of the label firmly on to the container. The endless belt 80 rolls the container off the rest 81 on to the plane surface 99 which is spaced apart from the lower run of the belt 80 a distance similar to the diameter of the container so that the belt 80 rolls the container along the rubber strip 101 to apply the remainder of the label firmly around the container. The container continues its rolling movement to the discharge trough 107. Immediately prior to the engagement of the container by the belt 80 the label applying feet 63, 64 are raised out of engagement therewith.
- 15 When the gum plates are in their fully forward position the type block 40 is brought beneath the label box which again descends to print or stamp the number on to the bottom label in the pile. After this operation the label box is raised
- 20 again and the gum plates make their return movement ready to commence the next labelling operation.

What we claim is:

1. A machine for applying labels to cylindrical objects comprising an inclined chute element down which the objects roll gravitationally, a reciprocable rest adapted to receive only a single one of said objects, said rest being reciprocable across the lower end of said element so as to receive the lowermost of the objects on said element and move it to a label receiving position, gum plates, means to apply gum to the gum plates, means to apply the exposed label of a stack of labels to the gum plates, means to reciprocate the gum plates in a plane transverse to the plane of reciprocation of the rest with pauses at the label receiving position and at a label transfer position adjacent the rest, means for pressing part of the label carried by the gum plates on to the object on the rest, a plane element, an endless belt means having part thereof parallel to and spaced from said plane element and having an extending end beyond one end of said plane element, and means for reciprocating the rest as aforesaid and to move the rest after the object thereon has received a label towards said belt means thereby contacting the object with the extending end of said belt means so that the latter rolls the object off the rest and along said plane element.
2. A machine for applying labels to cylindrical objects comprising an inclined chute element down which the objects roll gravitationally, a reciprocable rest adapted to receive only a single one of said objects, said rest being reciprocable vertically across the lower end of said element so as to receive the lowermost of the objects on said element and move it to a label receiving position, the upper end of said rest being inclined in the same sense as said element, a stop engageable by the object to limit its movement on to the rest, gum plates, means to apply gum to the gum plates, means to apply the exposed lowermost label of a stack of labels to the upper surface of the gum plates, means to reciprocate

the gum plates in a horizontal plane transverse to the plane of reciprocation of the rest and to the direction of movement of said objects on said element with pauses at the label receiving position and at a label transfer position adjacent to the rest, vertically reciprocable means located above the rest for pressing part of the label carried by the gum plates on to the object on the rest, a plane element disposed above and extending in the same direction as said chute element, an endless belt means having part thereof above parallel to and spaced from said plane element and having an extending end beyond one end of said plane element over the rest, and means for reciprocating the rest as aforesaid and to move the rest after the object thereon has received a label towards said belt means thereby contacting the object with the extending end of said belt means so that the latter rolls the object off the rest and along said plane element.

3. A machine for applying labels to cylindrical objects comprising a plane element along which the objects can be rolled, a reciprocable rest adapted to receive the objects one at a time and adapted to reciprocate across one end of said element, gum plates reciprocable transversely to the line of reciprocation of said rest and transversely to the direction of the rolling movement of the objects along said element, means for applying gum to said gum plates, means to apply labels one at a time to said gum plates, means to reciprocate said gum plates with a dwell at the label receiving position and a dwell at a transfer position adjacent to the rest, means to press the label on the gum plates on to the object on the rest while the gum plates dwell at the transfer position, endless belt means having a part parallel to and spaced from said element and having a part extending beyond one end of said element over the rest, and means for reciprocating said rest to bring the object into contact with said extending part of said belt means whereby the object is rolled off the rest on to and along said element.

4. A machine for applying labels to cylindrical objects comprising a plane element along which the objects can be rolled, a vertically reciprocable rest adapted to receive the objects one at a time and adapted to reciprocate across one end of said element, said rest having an upper inclined surface, a backstop at the lower side of said surface, gum plates reciprocable in a horizontal plane transversely to the line of reciprocation of said rest and transversely to the direction of the rolling movement of the objects along said element, said gum plates having an opening between them, means for applying gum to said gum plates, vertically reciprocable means to apply labels one at a time to the upper surfaces of said gum plates, means to reciprocate said gum plates with a dwell at the label receiving position and a dwell at a transfer position adjacent to the rest, means to press the label on the gum plates through said opening on to the object on the rest while the gum plates dwell at the transfer position, endless belt means having a part parallel to and spaced from said element and having a part extending beyond one end of said element over the rest, means for reciprocating said rest to bring the object into contact with said extending part of said belt means whereby the object is rolled off the rest on to and along said element, said label pressing means comprising feet on either side of the belt means to engage the label at spaced positions, and

means to maintain the feet engaged with the label as the object is moved up towards the belt means.

5. A machine for applying labels to cylindrical objects comprising means for feeding the objects, a receiving device for receiving the objects consecutively one at a time from said means, means for applying a gummed label to the object on the receiving device at one part of its length, an element providing a plane surface, and endless belt means for rolling the object off the receiving device on to and along the said plane surface thereby to roll the label on the object and apply it firmly thereto.
- 10 6. A machine for applying labels to cylindrical objects comprising a downwardly inclined feed chute down which the objects roll gravitationally, a reciprocating rest which receives the objects one at a time from the lower end of the said chute, a reciprocating label applying device operatively associated with said rest by which a gummed label is applied to the object on the rest at one part of the length of the label, an element providing a plane surface, and an endless conveyor belt spaced from and parallel to the plane surface, the said rest after application of the label to the object thereon being moved to bring the object into contact with the endless conveyor which rolls the object off the rest on to and along the plane surface.

20 7. A machine as claimed in claim 6 wherein the feed chute, the plane surface and the conveyor belt are disposed one above the other whereby the objects are fed back along the chute to a position adjacent that at which the objects are fed to the chute.

- 25 8. A machine for applying labels to cylindrical objects comprising means for feeding objects, a reciprocating rest for receiving one object at a time from said means, reciprocating gum plates, means for applying gum to the gum plates, means for bringing an exposed label of a stack of labels into contact with the gummed surface of the said plates, means for moving the gum plates from the gum receiving position to the label receiving position and then to a transfer position adjacent to said rest, means for pressing the label carried by the gum plates on to the object on the said rest, an element providing a plane surface, and an endless conveyor belt spaced from and parallel to the plane surface, the said rest after application of the label to the object thereon being moved to bring the object into contact with the endless conveyor which rolls the object off the rest on to and along the plane surface.

30 9. A machine as claimed in claim 8 wherein the reciprocating gum plates are constituted by a flat substantially rectangular metal plate having a substantially rectangular opening or cutting out at one end, said opening being of a width sufficient to support a label by its edges, and the means for moving the gum plates cause the gum plates to pause during the reciprocating movement thereof at a position where the rest lies below and towards one side of the said opening and wherein the means for pressing the label includes a device which pushes a label lying on said gum plates through said opening on to the object on the rest.

- 35 10. A machine for applying labels to cylindrical objects comprising a reciprocating rest for receiving an object fed to the machine, a reciprocating gum plate having a rectangular opening, a label box assembly mounted for reciprocating movement transversely to the plane of movement

of the gum plates and adapted to support a stack or pile of labels, means to apply a label which has been gummed by contact with the gum plates during reciprocation thereof to the object on the rest, the upper end of said rest being inclined in the same sense as said element, and a stop engageable by the object to limit its movement on to the rest.

11..A machine for applying labels to cylindrical objects comprising a plane element along which the objects can be rolled, gum plates, means for gumming the gum plates, means for applying labels one at a time to the gum plates, means for supporting the objects one at a time, means for pressing the label on the gum plates on to the object, endless belt means having part thereof parallel to and spaced from said plane element and having another part extending beyond one end of said element, and means for moving the supporting means to bring the object with its label into contact with said extending part whereby the object is rolled off the supporting means on to and along said plane element.

12. Machine as claimed in claim 11 wherein the reciprocating gum plates are constituted by a flat substantially rectangular metal plate having a substantially rectangular opening or cut-out at one end, said opening being of a width sufficient to support a label by its edges.

13. Machine as claimed in claim 3, wherein a wiper blade is provided at the end of the plane element to contact one end of the label and affix it to the object during upward movement of the rest.

14. A machine as claimed in claim 3 wherein the gum plates have an opening therein across which the label is applied and the rest is disposed to one side of the opening nearer to the plane element whereby the label applied to the object has one extending short end and an extending long end, and wiper means is provided at the end of the plane element adjacent to the rest which wipes the short end of the label around the object before the latter is rolled on to the plane surface.

ROBERT JOHN NEWMAN.
